UNITED STATES PATENT OFFICE.

RICHARD S. TYRES, OF BROOKLINE, MASSACHUSETTS.

PROCESS AND APPARATUS FOR HEEL MANUFACTURE.

1,350,852.

Specification of Letters Patent. Patented Aug. 24, 1920.

Application filed October 6, 1917, Serial No. 195,047. Renewed May 22, 1920. Serial No. 383,546.

To all whom it may concern:

Be it known that I, RICHARD S. TYRES, a citizen of the United States, and resident of Brookline, in the county of Norfolk and State of Massachusetts, have invented an Improvement in Processes and Apparatus for Heel Manufacture, of which the following description, in connection with the accompanying drawings, is a specification, 5 like letters on the drawings representing like parts.

My present invention is an improved process of, and apparatus for, manufacturing boot and shoe heels of pulp material.

15 In the art of making integral, non-laminated pulp heels, such, for example, as shown by my prior application 31865, filed June 3, 1915, I have discovered that such pulp heels can be made by means of a centrifugal apparatus which will be capable of receiving the pulp material as a mass, separating said mass automatically into substantially equal portions, each suitable for 20 subsequent compression into a heel, said apparatus containing means for both preliminarily shaping and molding individual heel mass, and with means for automatically giving a substantially final molded form to each heel mass, together with provision for 25 handling the pulp and eliminating the water content therefrom.

The handling of a large compact mass of pulp material, such as is necessary for subsequent molding and forming into a boot 30 or shoe heel, presents many difficulties. In order to handle such a suitable prepared mass of pulp, it is necessary to take the same while in a plastic or mobile state during the process of manufacture, viz., while the pulp 35 contains a sufficiently large amount of liquid to enable it to be handled. The elimination of this liquid from the mass of pulp presents an extremely difficult problem, and one which is vastly different from the making of 40 pulp into thin sheets, where the straining of the liquid and drying of the sheet material is a well known and comparatively easy process.

In my prior application, Ser. No. 126,425, 45 filed October 18, 1916, I have explained and described one method of manufacture for making pulp wood heels, which method included the step of separating a predetermined mass of pulp material by measuring 50 and mechanical means of subsequent handling of each heel mass by molding and

forming appliances, squeezing out the liquid content by compression. Another method of making such heels is described and claimed in my prior application Ser. No. 153,881, filed March 10, 1917, wherein suitable binders are employed to solidify and harden, automatically, the individual heel pulp mass, either with or without compression by heavy molding appliances, preferably utilizing only such molding pressure as will shape the pulp material. In my present application, however, I propose to handle the pulp mass and to eliminate the liquid therefrom, in a distinctly novel manner as applied to pulp heel manufacture, relying upon centrifugal force to eliminate the liquid from each heel mass of pulp, as well as relying upon this centrifugal action to separate a predetermined mass of pulp 60 suitable for a plurality of heels, into the heel molds. When so separated I maintain the centrifugal force to actually shape or mold the individual heel mass, and utilize additional compression devices, acting by 65 centrifugal force, to give the heel mass its 70 final form, and compression. It will be understood that the present process and apparatus contemplate the use of a suitable pulp mass, such as explained in my said 75 prior application 126,425, without any self-hardening binder, or a pulp mass as explained in my prior application Ser. No. 153,881, which includes a self-hardening 80 and solidifying binder. 90

Referring to the drawings, illustrating a preferred embodiment of the invention,

Figure 1 is a view, partly in cross section of a centrifugal apparatus suitable for carrying out my improved process herein explained;

Fig. 2 is an enlarged plan view, partly in cross section, of the centrifugal molding apparatus;

Fig. 3 is an enlarged detail cross sectional view of one of the molders;

Fig. 4 is an enlarged view partly in cross section of the compressing plungers; and

Fig. 5 is a detailed view of the ejecting apparatus.

In carrying out the present process, I prefer to utilize a centrifugal type of machine having a suitable number of molding pockets, six such molds being herein shown, all contained within a cover or drum 1 110 mounted upon suitable pedestals as indicated at 2, secured to a base 3. In the center of

the lower portion of the drum 1 is a bearing 4 adapted to receive a central shaft 5, extending upwardly, and with its lowermost end sustained on a thrust bearing at 6 on the base 3, a pulley 7 being keyed on the shaft 5 adjacent thereto. To rotate the shaft 5 any means may be provided, preferably an individual motor 10 is provided, which may conveniently rest on a bracket 11, 10 said motor having a drive pulley 12 from which a belt 13 leads to the shaft pulley 7 around guide pulleys at 14, mounted in arms 15 extending from the standard 16, which is carried by the base 3, as 15 clearly shown in Fig. 1. Operation of the motor 10 thus rotates the shaft 5 at the desired rate of speed. Secured to the shaft 5 within the drum 1 is a carrier 20, with its hub 21 rigidly secured to the shaft 5. 20 This carrier has about its periphery the six molding pockets 22, 22, extending radially therefrom. As a secure and economical means of securing these pockets to the carrier 20, I prefer to form vertically extending flanges 23, around the periphery of the carrier 20, having the same slotted to receive each pocket 22, the latter being formed with flanges 24 adapted to bear in and interlock with corresponding recesses 25, formed 25 in the flange 23, which are adjacent openings 26 through said flange, of equal extent to the mouth 27 of each pocket 22. 30 This construction contemplates the interchangeability of different molders 22 for different shaped heels, each of said molds being of suitable size, and with flanges to fit in the recesses provided therefor in the carrier 20, but with the rearmost portion of the mold of any configuration which it is 35 desired shall be given to the finally molded pulp heel. As illustrated in the drawings, these molds may conveniently comprise a beveled opening or flange portion, as shown at 30, a substantially straight section as indicated at 31, through which a plunger may be adapted to reciprocate, as will be explained, and a final heel shaping and molding portion 32, of appropriate size and contour to receive the molded heel in its finally 40 compressed form, extending from the position of the mold to the dotted line 33 as indicated in Fig. 1. The extreme end or bottom of the mold I prefer to form as a movable plate 34, preferably perforated, through 45 which the moisture may be thrown during the operation of the apparatus, and which plate 34 may thereafter be employed as an ejector, being moved lengthwise of the mold from its seat 35 inwardly so as to throw out 50 the completed heel, a rearwardly extending arm 36 and pin 37 thereon being provided, as will be explained. This plate 34 has a plurality of small perforations 38 (see Fig. 5) sufficiently small to prevent the pulp being compressed therein and sufficiently nu-

merous to permit the liquid to escape from the pocket or end of the mold, said liquid emerging from the opening 39 in the end of the mold through which the arm 36 extends, and collecting in the bottom of the 70 drum 1, from which it may be subsequently withdrawn through the valve 40.

The top of the drum 1 is opened and a removable cover 41 fitted thereon. When this cover is removed, a predetermined mass of 75 pulp material, sufficient to fill the six molds 22, may be poured into the flanged carrier 20, which latter has beveled faces as indicated in dotted lines at 42, the motor 10 started, the shaft 5 rotated, and the mass 80 of pulp material contained within the carrier 20 will be automatically and equally distributed into each of the six molds 22, being thrown into the extreme heel or pocket of each mold against the perforated plate 85 34, and the liquid quickly eliminated therefrom by centrifugal action, as will be readily understood. This also secures sufficient compressing force to effect a substantial molding of the pulp, still further compressing and solidifying the mass of pulp material in each mold as the liquid is eliminated therefrom. The process thus far described will both separate from the mass of pulp material a suitable amount for subsequent 90 formation into an individual heel, will drain out the liquid, will give a molding or shaping action to the heel, and will enable a satisfactory commercial molded pulp heel to be made in an expeditious and economical 95 manner.

In order to provide a complete molding action by means of plungers adapted to fit within each mold, I provide means which may be lowered into the carrier 20, then released while the shaft 5 and carrier 20 are being rotated at a high velocity, and a plunger will thus be thrown into its adjacent mold, giving a final compression and a desired concavity or configuration to the top 110 of the heel, as a completing molding action, further forcing out the moisture and solidifying the pulp fiber.

In carrying out this further step in a preferred form, I fit upon the upper portion 115 of the shaft 5 by a sliding or splined key, or by having the shaft squared, a hub 44, carrying an arbor or spider formed with radial arms 45 and a peripheral rim 46. The rim 46 is perforated at a plurality of 120 points, 47, 47, each in alignment with a mold 22, and through each perforation is fitted a sleeve 48, having at its inner end a collar 49 and carrying a plunger 50 having on its outer end, outside of the rim 46, a 125 heel engaging mold 51. Preferably the face of this mold 51 is convexed to give the usual concavity to the top of a heel, as indicated in Fig. 4. The sleeve 48 has its outer end next the mold 51 partially closed at 52, thus 130

affording a bearing for the plunger 51 and a stop for the rim or shoulder 53 on its inner end. The sleeve 48 is adapted to slide through the opening 47 until the adjustable 5 nut 49 strikes against the rim 45, then the plunger 51 may continue its sliding action through the opening in the sleeve 48 until the shoulder 53 strikes against 52. Preferably, however, the final compression of the 10 heel mass within the end of the mold 22, will act to limit the movement of the mold 51, the positive stop afforded by the shoulder 53, however, limiting an excessive compression of the pulp. To control the sliding 15 action of these plungers, and to release them simultaneously when the hub 44 and spider containing the plungers is lowered down to the bottom of the container 20 (see Fig. 1), I provide a plurality of cords 55, leading 20 from an eyelet 56 in the rearmost face of each plunger 51, through a pulley 57 journaled on standards 58 secured to the hub 44 and thence upwardly through a guide 59 to a sliding collar 60 positioned on the 25 upper part of the shaft 5, to which the cords 45 are secured. The hub 44 being splined on the shaft 5 rotates with it, carrying the plungers at same rotation as that of the member 20 and the molds 22. After 30 the pulp has been centrifugally thrown into each mold, the hub 44 is then lowered until it strikes against the bottom of the carrier 20, a plunger being alined with each mold in this position. The collar 60 is then released, as by loosening the set screw 61, and the sleeves 48, plungers 50 and the molds 51 at once are thrown outwardly 35 into their respective adjacent molds 22, striking against the heel mass in the pocket of each mold and giving a final compressing, 40 shaping and forming action. The motor is then stopped, the collar 60 moved upwardly, withdrawing the plungers and sleeves, and the hub elevated above the carrier 20 to permit 45 the completed molded heels to be ejected from each mold. Each mold 22 may be detachable from the carrier, if desired, and the heel mold quickly thrown out, but I prefer to provide means to eject the molded heel 50 with the mold 22 in position in the carrier. To this end I provide a recess 62 through the drum 1 in alinement with the arm 36, extending outwardly from each mold. The carrier 20 may be rotated by hand, until a mold 22 is in alinement with the opening 62, whereupon the ejector 64, preferably having a forked end 65 to coöperate with the correspondingly angled end of the arm 36, is fitted thereto, a movable latch 66 pivoted at 67 to said ejector and having a forked hooked end 68 to catch on the pin 37, is applied. the mold 34 shoved inwardly until the heel is thrown into the carrier 20, and then the ejector 64 withdrawn, leaving 65 the plate 34 in the pocket of the mold as

before. I prefer to form the hook 68 substantially as illustrated at 69, Fig. 5, so that the hook will be automatically raised and released when the plate 34 strikes against the base 35 of its mold, although as 70 the entire latch 66 is then outside of the mold, it can be lifted by hand and released if desired. The next mold 22 is then swung into position and its heel ejected therefrom in like manner. 75

My present process and apparatus thus effect an automatic distribution and separation of the plastic and mobile pulp mass while it has a sufficient liquid content to insure its rapid flow into the molds, providing 80 means for the elimination of the liquid, the compacting of the pulp, and the final solidifying and substantial drying and molding of the pulp, all as a substantially consecutive and almost a simultaneous operation. 85 This insures accuracy, speed in manufacture, economy in cost and uniformity of product. I believe the handling of a pulp mass sufficiently large and while in its pulpy or plastic state, for subsequent compression 90 into heel molds, is a distinct novelty, and I therefore wish to claim the same broadly. I also believe that the utilization of means which will simultaneously eliminate the liquid content, mold the pulp into both preliminary and final heel form, is also distinctly new, and is therefore claimed herein. 95

I have discovered that the centrifugal action on a mass of fibrous pulp material has a peculiarly beneficial action in the manufacture of a heel, because the fiber of the pulp is laid in a substantially stratified mass, thus greatly improving the wearability, finish receiving qualities and breasting and trimming of a heel. With the pulp fiber thus 100 stratified, the heel breast operation, for example, on a fiber heel made by this process, cuts the heel breast in a clean smooth manner, so as to practically eliminate the necessity of subsequent scouring, buffing or the 105 like. Also the capacity of such a molded heel for receiving inking, stains, blacking, wax finishing or the like, is greatly improved over a pulp article molded by any other process of which I am aware. The 110 action of the plunger giving the final compressing and molding pressure on the pulp, is also extremely beneficial in aiding to squeeze out or eliminate the water in the pulp, forcing the same therefrom and greatly aiding the centrifugal drying action. I find it advantageous in some cases to pour the entire predetermined mass, at once, into the central receptacle, but I contemplate the gradual pouring or feeding 115 the pulp mass into said central receptacle while the apparatus is rotating, thus still further aiding in the stratification of the fibers of the pulp and either operation is feasible with my apparatus herein shown, 120 125 130

and in carrying out the present process. I also contemplate the simultaneous ejection of all the molded heels, by any suitable means, throwing or drawing out the same, but have not at present developed this mechanism, which may be the subject of a later application, wherein I may utilize linings which are interchangeable inside the molds.

10 My invention is further described and defined in the form of claims as follows:

1. The improved process in the art of manufacturing boot and shoe heels from pulp material, which consists in applying a predetermined mass of pulp in a rotating receptacle, automatically, separating said mass of pulp into a plurality of equal parts, simultaneously discharging each part into a plurality of heel molds arranged around the 15 receptacle, and expressing the moisture therefrom, by centrifugal force, and finally, 20

compressing each portion in its respective mold.

2. Apparatus of the kind described, adapted to separate and mold pulp articles from 25 a predetermined mass of plastic pulp material, consisting in a vertical shaft, a table attached to the shaft for rotation therewith, a plurality of molds defining a centrally located pulp receiving chamber, means to 30 permit the liquid to escape from said molds, and a plunger for each mold, operable at a predetermined time on the pulp material in each mold.

In testimony whereof, I have signed my 35 name to this specification, in the presence of two subscribing witnesses.

RICHARD S. AYRES.
